UNITED STATES PATENT OFFICE.

HENRY ANDREW KENT, OF BOUNDS GREEN, AND HAROLD GEORGE LACELL, OF FINCHLEY, ENGLAND, ASSIGNORS TO SILICA SYNDICATE LIMITED, OF LONDON, ENGLAND.

MERCURY OR OTHER VAPOR ELECTRIC LAMP.

No. 923,124.

Specification of Letters Patent.

Patented May 25, 1909.

Application filed October 8, 1908. Serial No. 456,066.

To all whom it may concern:

Be it known that we, HENRY ANDREW KENT, a subject of the King of Great Britain, residing at The Poplars, Maidstone road, 5 Bounds Green, in the county of Middlesex, England, engineer, and HAROLD GEORGE LACELL, a subject of the King of Great Britain, residing at Ardoch, Nether street, Finchley, in the said county of Middlesex, 10 England, chemist, have invented new and useful Improvements in Mercury or other Vapor Electric Lamps, of which the following is a specification.

This invention has for its object to provide 15 mercury, or other metallic vapor lamps which are simpler and more economical in construction, and more convenient in use than are such lamps as hitherto made, the lamps in accordance with this invention being made so that there is no necessity for the 20 seals and vacuum hitherto necessary in mercury, and other vapor lamps.

The lamps in accordance with this invention may employ mercury, or any other 25 metal, or amalgam, or alloy of metals or any suitable substances or compounds which will become vaporized at the working temperature of the lamp, but for brevity of description we will presume that mercury is used.

According to this invention the lamp consists of, or comprises a chamber, for instance a tube, made of quartz-glass or other suitable material, which tube is in communication with a container or containers, of mercury, 35 which container or containers, is or are open at top, or only sufficiently closed to exclude dirt, and are so arranged that, when the lamp is not in operation, the mercury will fill the said tube, and when the lamp is 40 brought into operation, and the requisite heat is supplied to the said tube, the mercury will vaporize in the said tube, and an arc will be formed, the vapor pressing back the liquid mercury into the said container, or containers, through openings so restricted that they 45 will permit only slow passage of the mercury therethrough, thus, preserving a steady arc. The mercury will slowly return and fill the tube, again when the current is shut off from 50 the lamp, and thus be in readiness to be brought again into operation when required without the manipulation hitherto necessary to bring the mercury into the space in which it is vaporized.

In the accompanying drawings, Figure 1

is a vertical section of a lamp embodying our invention in one form; Figs. 2, 3 and 4 are similar views of modified constructions of the tube portion.

Referring to Fig. 1, a tube 1 of quartz-glass has formed, or attached, at each turned-up end a cup (2 and 3) communicating with the tube 1 by contracted openings, or passages, 4 and 5, to keep the mercury steady under the pressure of the vapor of mercury 60 formed in the tube 1. We have found that to obtain this steadiness of the mercury (and consequently of the arc), the said openings, or passages, should not have a cross-sectional area materially exceeding one twentieth of the cross-sectional area of the tube in which the arc is produced. A resistance wire 6, is arranged in any suitable manner, for instance wound around said tube 1 and a current passed through the same to generate 70 heat to effect the vaporization of mercury at the point required. The tube 1 may be contracted at its mid-part 7 to receive the coils of the said resistance wire 6, so that it heats the tube 1 preferably midway between the 75 cups 2 and 3, and the respective ends of the tube 1. The terminals 8 and 9 of the electric conductors enter the respective cups 2 and 3 and are in contact with the mercury therein. The whole arrangement is supported in any suitable insulating body-part, or holder. As shown, the socket-piece 10 carries a hood 11, which carries supports 12 embracing the cups 2 and 3. The electrical connections are preferably arranged as shown 80 so that the electric current passes first through the heating resistance 6 and thence to the terminal wire 8 in the mercury in the cup 2, and then (when the lamp is in operation) through the mercury on one side and 85 the vapor of mercury in the tube 1, and through the mercury in the other side and in the cup 3, and out by the terminal wire 9, which dips into the said mercury, all as indicated by the arrows.

When the current is put on to the lamp, vapor of mercury is, by the heat of the resistance 6, formed in the part of the tube 1 surrounded by the resistance, and the arc across the vapor emits light, the pressure of the vapor forcing the liquid mercury toward each end of the tube 1, so that the mercury slowly rises into the space in each cup (2 and 3), through the contracted openings, or passages, 4 and 5, forming the communications. 100 105 110

between the cups 2 and 3 and the tube 1, these contracted passages thus giving steadiness of the arc. When the electric current is discontinued and the tube 1 is no longer sufficiently heated to vaporize mercury, the vapor condenses and the part of the tube 1 which was filled with vapor becomes again filled with liquid mercury ready for re-vaporizing and forming an arc as before, when the electric current is again put on to light the lamp.

The cups 2 and 3 may be closed at top by any suitable means sufficient to exclude dirt, but they need not be closed hermetically.

15 The resistance wire 6 may be of any suitable metal, or alloy, not readily oxidized when heated, for example iridio-platinum is a very suitable alloy.

Figs. 2, 3 and 4 illustrate diagrammatically some modifications. In these figures the parts which correspond with those shown in Fig. 1 are marked with the same reference numerals and the arrows indicate the direction of the current.

25 In Fig. 2 the terminal wires 8 and 9 pass through the contracted openings, or passages 4 and 5 so as to give the necessary very restricted passage-ways to and from the cups 2 and 3 without undue heating, the restriction of the passage-ways allowing but slow movement of the mercury and consequently keeping the incandescent vapor steady in the tube 1. In this figure the resistance wire 6 is shown coiled around an extension from 30 the tube 1.

In Figs. 3 and 4 the ends of the tube 1 are enlarged at 13, and in these figures and in Fig. 2 the tube 1 is not contracted at its mid-part.

40 In Fig. 4 is shown a means for short-circuiting the resistance wire 6 by bringing a by-pass wire 14 into the cup 3, to such a position that, when the mercury rises to any predetermined height in the said cup, the 45 mercury makes contact with the said wire 14 and the current enters the mercury in the cup 3 without first passing through the resistance wire 6.

If desired there may be a piece of material 50 15 not acted upon by mercury, or other vaporizable matter used (such as iridium, or tantalum, for example), at one end, or at both ends, of the tube 1, as shown at one end in dotted lines in Fig. 3 to prevent vaporization of the mercury or the like, at that end, or those ends, interfering with the action of the lamp.

We are aware that it has before been pro-

posed to make vapor electric lamps with a tube heated by a wire coiled around it for the purpose of starting the lamp and having a receptacle for mercury at each end and with means for cutting off the heating current when not required, and we do not claim such features as our invention.

65 We claim as our invention:

1. A vapor lamp having a tube of quartz-glass, with, at each end, a cup communicating with the tube by a contracted passage not materially exceeding in cross-sectional area one twentieth of the cross-sectional area of the tube in which the arc is produced and a resistance wound so as to heat the said tube together with electrical connections for passing a current of electricity through the said resistance and the vaporizable material contained in the said tube, there being a space in each cup above the said material, so that when an electric current is passed through the resistance and said material is in part vaporized, the unvaporized portions of the same are in part forced through the contracted passages into the spaces in the said cups whereby unsteadiness of the arc is prevented and the return of said material to the tube is insured upon the cutting off of the electric current and the consequent condensation of the vapor formed, substantially as described.

2. In a vapor lamp of the type described, a stationary vapor tube adapted to contain the material vaporized and a container located above said tube and communicating therewith by a constricted passage through which said material can be only slowly forced by the vapor generated during the operation of the lamp, whereby the arc is steadied, as described.

3. In a vapor lamp of the type described, a stationary vaporizing tube adapted to contain the material vaporized and a container at atmospheric pressure located above said tube and communicating therewith by a constricted passage through which said material can be only slowly forced by the vapor generated during the operation of the lamp, whereby the arc is steadied, as described.

In testimony whereof we have signed our names to this specification in the presence of two subscribing witnesses.
